UNITED STATES PATENT OFFICE.

CLARENCE A. BODDIE, OF PITTSBURGH, PENNSYLVANIA, ASSIGNOR TO WESTINGHOUSE ELECTRIC AND MANUFACTURING COMPANY, A CORPORATION OF PENNSYLVANIA.

FURNACE-REGULATOR SYSTEM.

Application filed November 13, 1919. Serial No. 337,687.

To all whom it may concern:

Be it known that I, CLARENCE A. BODDIE, a citizen of the United States, and a resident of Pittsburgh, in the county of Allegheny and State of Pennsylvania, have invented a new and useful Improvement in Furnace-Regulator Systems, of which the following is a specification.

My invention relates to regulator systems and particularly to regulator systems for governing the operation of the movable electrodes in electric furnaces.

One object of my invention is to provide a furnace-regulator system that shall govern each movable electrode, not only in accordance with the current flowing through it but also in accordance with the potential difference obtaining between the neutral point of the supply circuit and the bath of material being treated to maintain equal heating effects by the various electrodes, and that shall be so operated as to prevent hunting action.

In operating electric furnaces of the movable-electrode type, and, particularly, if the furnace is connected to a three-phase supply circuit, considerable trouble is generally experienced in obtaining equal heating effects by the various electrodes or in obtaining a fixed ratio of heating effects by the various electrodes. Such uneven heating effects are liable to be experienced if a charge having an uneven resistance throughout its structure is being treated in the furnace. In case the electrodes of the furnace produce unequal heating effects, the lining of the furnace is not subjected to an even temperature and, consequently, the length of time which the furnace may be operated without repairs is greatly reduced. Thus, the producing of unequal heating effects by the various electrodes is liable to impair the value of the material being treated in the furnace and, moreover, to cause a more rapid deterioration of the furnace than would be effected if the ratio of the work performed by the various electrodes were maintained substantially constant.

In an electric furnace constructed in accordance with my invention, each movable electrode is provided with means for so adjusting it that the ratio of work performed by the various electrodes shall be maintained substantially constant, irrespective

of the operating conditions of the furnace, and, moreover, means is provided for insuring the system against hunting action.

More specifically, my invention relates to an electric furnace having three movable electrodes which are connected to a three-phase supply circuit. Each of the electrodes is provided with a motor for raising and lowering it and each motor is provided with a regulator for operating it to maintain the ratio of the heating effect produced by the associated electrodes to the heating effects produced by the remaining electrodes substantially constant. Each of the regulators embodies an electromagnet having two windings which operate two switches for governing the operation of the motor associated with it. One of the windings of each of said electromagnets is energized in accordance with the current flowing through the associated electrode, and the second winding of each electromagnet is energized in accordance with the potential existing between an artificial neutral point of the supply circuit and the bath of material being treated. Thus, each electrode is not only controlled in accordance with the current flowing through it but also is governed in accordance with the potential conditions of the electrode circuit. The current passing through the second winding of each electromagnet will have such phase relation to the current passing through the first winding as to add to, or subtract from, the energizing effect of the first winding, according to whether the associated electrode is being operated to produce a greater or a less than normal portion of the heating effect of the furnace. Moreover, means is provided which is operated by the two switches for varying the energization of the current winding in each regulator to prevent hunting action.

This invention is an improvement on the furnace-regulator system disclosed in the patent application Serial No. 288,832, filed April 9, 1919, by Robert D. Evans and assigned to the Westinghouse Electric & Manufacturing Company, and reference may be had to the above application for an analysis of the phase relation of the currents flowing through the current and potential windings of the main magnet of the regulator.

The single figure of the accompanying drawing is a diagrammatic view of a regulator system constructed in accordance with my invention.

5 Referring to the drawing, an electric furnace 1, comprising a receptacle 2 containing a bath of material 3, is provided with three movable electrodes 4, 5 and 6 which are directly connected to a three-phase supply circuit comprising conductors 7, 8 and 9.

10 Each of the movable electrodes 4, 5 and 6 is provided with a motor for raising and lowering it and a regulator for so governing the electrode motor as to maintain the ratio 15 of heating effects by the various electrodes substantially constant. Inasmuch as the electrode motors and the associated regulators are similar in construction and operation, it is deemed sufficient to illustrate and 20 describe but one motor and one regulator, namely, the motor and regulator which are associated with the movable electrode 6.

25 A motor 10, comprising an armature 11 and a field winding 12, is provided for raising and lowering the electrode 6 to maintain a substantially constant heating effect by the electrode. The field winding 12 is directly connected to an auxiliary supply circuit comprising conductors 13 and 14, and the armature 11 is selectively connected to the supply conductors 13 and 14 by means of two switches 15 and 16. The motor 10 is mechanically connected to the electrode 6 in any suitable manner, as by means of a winding 35 reel 17 and a flexible connector 18 which passes over a pulley 19.

30 A regulator 20, comprising a main control electromagnet 21 and the two switches 15 and 16, is provided for governing the operation of the motor 10, not only in accordance with the current flowing through the electrode 6 but also in accordance with the potential obtaining between an artificial neutral point of the supply circuit and the 35 bath of material 3 being treated in the furnace. The main control electromagnets for the regulators which govern the operation of the electrodes 4 and 5 are designated by the reference characters 23 and 22.

40 50 The main control electromagnet 21 embodies a current winding 24 having taps 25, 26 and 27 extending from it, a potential winding 28 and a core armature 29. The core armature 29 is provided with a dash pot 30 for adjusting the speed of its operation and is pivotally connected to a contact arm 31. The current winding 24 is connected to the three-phase supply conductor 9 by means of a transformer 32 in order to 55 be energized in accordance with the current flowing through the electrode 6. The potential winding 28 is connected across two conductors 33 and 34 which are respectively connected to the bath of material 3 being 60 treated and an artificial neutral point of the 65

supply circuit comprising conductors 7, 8 and 9.

The neutral point of the supply circuit is obtained in a well known manner by means of two windings 35 and 36. The winding 35 is connected across the supply conductors 7 and 9, and the winding 36 is connected between the supply conductor 8 and a tap extending from the center of the winding 35. When two windings are so connected, the 70 neutral point of the three-phase circuit is obtained by a tap from the winding 36 which divides the winding 36 in the ratio of 2 to 1. In brief, the neutral point of the supply circuit is represented by the potential existing in the winding 36 at a point one-third of its length from the point of connection to the winding 35. The tap 37 from the winding 36 is directly connected to the conductor 34. Inasmuch as the above described means for obtaining an artificial neutral point in a supply circuit is well-known, it is deemed unnecessary to make a complete analysis of the potentials obtaining in the two windings when so connected.

75 The main control magnet 22 is provided with a current winding 38, which is connected to the three-phase supply conductor 8 by means of a current transformer 39, and with a potential winding 40 which is connected across the conductors 33 and 34. The main magnet 23, which is associated with the electrode 4, is provided with a current winding 41 which is connected to the three-phase supply conductor 7 by means of a current transformer 42, and a potential winding 43 which is connected across the conductors 33 and 34.

80 85 The contact arm 31 is fulcrumed at 44 and carries a main contact member 45 which engages contact members 46 and 47, according to the operative position of the main magnet 21. Upon engagement between the contact members 45 and 46, a circuit is completed from the supply conductors 13 and 14 for operating the switch 16 and, upon engagement between the contact members 45 and 47, a circuit is completed for operating the switch 15.

90 95 100 105 110 115 120 125 130 The switch 15 comprises a winding 48 and a core armature 49 which is controlled by it. The core armature 49 is directly connected to two switch members 50 and 51 and two interlock switch members 52 and 53. The two switch members 50 and 51 serve to connect the armature 11 across the supply conductors 13 and 14 for effecting counter-clockwise rotation of the motor 10. The counter-clockwise rotation of the motor 10 raises the electrode 6 to decrease the current flow through it. The interlock switch member 53 serves, upon operation of the switch 15, to short-circuit that portion of the winding 24 which is included between the taps 25 and 26 for decreasing the energization of the

main magnet to prevent any hunting action when the electrode is being raised from the bath of material.

The switch 16 comprises a winding 54 and 5 an armature 55 which is controlled by it. The armature 55 is directly connected to two switch members 56 and 57 and two interlock switch members 58 and 59. The two switch members 56 and 57 serve to connect the 10 armature 11 across the supply conductors 13 and 14 for operating the motor 10 in a clockwise direction to lower the electrode 6 in the furnace. The interlock switch member 59, upon operation of the switch 16, serves to 15 open a short-circuit which normally obtains across that portion of the winding 24 which is included between the taps 26 and 27. Such operation of the interlock switch member 59 serves to prevent any hunting action 20 when the electrode 6 is being lowered in the furnace.

When the two switches 15 and 16 are de-energized, the two interlock switch members 52 and 58 complete an energizing circuit 25 from the supply conductors 13 and 14 for a brake relay 60. The brake relay 60 completes a dynamic-braking circuit for the armature 11 through a resistor 61.

Assuming that the electrode 6 is performing more than its normal portion of the work 30 of the furnace 1, there is either an increased current flow through the electrode 6 or an unbalancing of the phase relation of the current flow through the electrodes 4, 5 and 6, the amount of which will be indicated by the potential obtaining between the neutral point of the supply circuit and the potential of the bath of material 3 being treated in the furnace. If an increased current flows 40 through the electrode 6, the energization of the winding 24 will be increased to operate the contact arm 31 and effect engagement between the contact members 45 and 47 and, if an unbalanced phase relation obtains, the winding 28, which is energized in accordance 45 with the potential existing between the neutral point of the supply circuit and the bath of material 3, will be energized to assist the winding 24 in moving the contact arm 31 to effect engagement between the contact members 45 and 47. Upon engagement between the contact members 45 and 47, a circuit is completed from the supply conductor 13, through the contact arm 31, contact mem- 50 bers 45 and 47 and the winding 48 of the switch 15, to the supply conductor 14. Thereupon, the switch 15 is operated to complete a circuit through the armature 11 for operating the motor 10 in a counterclock- 55 wise direction. The circuit through the armature 11 is traced from the supply conductor 13, through the switch member 51, armature 11 and the switch member 50 to the supply conductor 14.

60 In case no means were provided for pre-

venting any hunting action, the main control magnet 21 would be controlled solely by the circuit conditions of the electrode 6 and, consequently, the main magnet would not be operated to separate the contact members 45 and 47 and stop the motor until normal conditions obtained in the electrode circuit. Consequently, the inertia of the various moving parts of the regulator and the inertia of the armature would cause overtravel 70 and, accordingly, would raise the electrode 6 above the desired point to obtain normal operating conditions. In order to prevent such overtravel, and the consequent hunting action, the interlock switch member 53 is operated simultaneously with the operation of the motor 10 for short-circuiting a portion of the winding 24 to decrease the energization of the main magnet 21 and, consequently, to effect a separation of the contact 75 members 45 and 47 just prior to the obtaining of normal conditions in the electrode circuit.

In case the electrode 6 is performing less than its normal portion of the work of the 80 furnace, the energization of the winding 24 is decreased or the winding 28 is energized by a smaller current or by current having such power factor as to oppose the action of the current flowing through the winding 24 85 and thus permit the operation of the contact arm 31 to effect engagement between the contact members 45 and 46. Upon engagement between the contact members 45 and 46, a circuit is completed which 90 extends from the supply conductor 13 through the contact arm 31, contact members 45 and 46 and the winding 54 to the supply conductor 14. Thereupon, the switch 16 is operated for connecting the 95 armature 11 across the supply conductors 13 and 14 to operate the motor 10 in a clockwise direction. The clockwise rotation of the motor 10 lowers the electrode 6 to obtain 100 normal operating conditions.

In order to prevent any hunting action when the electrode is being lowered in the furnace, the interlock switch member 59 is operated, simultaneously with the operation of the motor 10, to open the short-circuit 110 which normally obtains across that portion of the winding 24 which is included between the taps 26 and 27. Thus, the energization of the main magnet 21 is increased and its setting is so changed as to effect separation 115 of contact members 45 and 46 just prior to the obtaining of normal conditions in the circuit of the electrode 6.

Although the operation of but one electrode has been described in detail, it should be noted that the main control magnets 21, 22 and 23 are operated to simultaneously adjust the three electrodes 4, 5 and 6 to maintain the ratio of work performed by them substantially constant. The current 120

flowing through the potential windings 28, 40 and 43 will have phase relations relative to the currents flowing through the windings 24, 38 and 41 to assist or to oppose the action of the windings 24, 38 and 41, according to the heating effects of the associated electrodes. For a complete analysis of the relations of the currents flowing through the potential and the current windings, reference may be had to the application Serial No. 288,832, above referred to.

Modifications in the system and arrangement and location of parts may be made within the spirit and scope of my invention, and such modifications are intended to be covered by the appended claims.

I claim as my invention:

1. In a furnace regulator system, the combination comprising a polyphase supply circuit, a plurality of movable electrodes connected thereto, means for automatically controlling each of said electrodes to equalize the heating effect of the various electrodes, and automatic means for preventing hunting action.

2. In a furnace-regulator system, the combination comprising a polyphase supply circuit, a plurality of movable electrodes connected thereto, a motor for raising and lowering each of said electrodes, means for operating each motor to equalize the heating effects produced by the various electrodes, and automatic means associated with each electrode for preventing hunting action.

3. In a furnace-regulator system, the combination comprising a three-phase supply circuit, three movable electrodes connected thereto, a motor for raising and lowering each of said electrodes, means for selectively operating said motors in accordance with the characteristics of the current supplied to the electrodes to equalize the heating effects produced by the various electrodes, and automatic means for preventing hunting action.

4. In a furnace-regulator system, the combination comprising a supply circuit, three movable electrodes connected to the supply circuit, means for adjusting said electrodes in accordance with the difference in potential between the bath of material being treated and the neutral point of the supply circuit, and means for insuring the system against hunting action.

5. In a furnace-regulator system, the combination comprising a supply circuit, three movable electrodes connected to the supply circuit, means for adjusting said electrodes in accordance with the difference in potential between the bath of material being treated and the neutral point of said supply circuit and in accordance with the current supplied to the electrodes, and means for preventing hunting action.

6. In a furnace-regulator system, the com-

bination comprising a three-phase supply circuit, three movable electrodes connected to the supply circuit, means controlled by the potential existing between the neutral point of the transformer and the bath of material being treated for maintaining the ratio of work performed by the various electrodes substantially constant, and means for insuring the system against hunting action.

7. In a furnace-regulator system, the combination of a polyphase supply circuit, a plurality of movable electrodes connected to said supply circuit, and a motor for raising and lowering each of said electrodes, of means comprising a main magnet having a current and a potential winding for controlling each motor to maintain a substantially constant heating effect by the associated electrode with respect to the other electrodes, and means for varying the energization of each current winding to prevent hunting action.

8. In a furnace-regulator system, the combination with a three-phase supply circuit, three movable electrodes connected to said circuit, and a motor for operating each of said electrodes, of means comprising a main magnet having a potential winding for neutralizing the potential between the electrodes and the bath of material being treated, said potential winding being energized in accordance with the difference in potential between the neutral point of the supply circuit and the bath of material being treated, and means for controlling said electrode magnet to prevent hunting action.

9. In a furnace-regulator system, the combination with a three-phase supply circuit, three movable electrodes connected to said supply circuit, and a motor for raising and lowering each electrode, of means comprising a main magnet having a current and a potential winding for controlling each electrode to maintain the ratio of work performed by the various electrodes substantially constant, each of said current windings being energized in accordance with the current flowing through the associated electrode and each potential winding being energized in accordance with the difference in potential between the neutral point of said supply circuit and the bath of material being treated, and means for varying the energization of said current windings to prevent hunting action.

10. In a furnace-regulator system, the combination with a polyphase supply circuit, a movable electrode connected to said supply circuit, and a motor for raising and lowering said electrode, of means comprising a main magnet having a current and a potential winding for operating the electrode to maintain a substantially constant heating effect by the electrode arc, said potential winding being energized in accord-

5 ance with the potential obtaining between the neutral point of the supply circuit and the bath of material being treated, and means for varying the energization of the current winding to prevent hunting action.

10 11. In a furnace-regulator system, the combination comprising a plurality of movable electrodes, means for maintaining a constant current flow through the electrodes and for equalizing the potentials across the various electrode arcs, and automatic means for preventing hunting action.

12. In a furnace-regulator system, the combination comprising a plurality of movable electrodes, means comprising a plural-
15 coil electromagnet operatively associated with each electrode for maintaining a pre-determined ratio of heating effects by the various electrodes and means for preventing hunting action.

20 In testimony whereof, I have hereunto subscribed my name this 27th day of Oct., 1919.

CLARENCE A. BODDIE.
